UNITED STATES PATENT OFFICE.

MICHAEL H. SULLIVAN, OF POUGHKEEPSIE, NEW YORK.

PISTON AND PISTON RING.

1,427,425.

Specification of Letters Patent. Patented Aug. 29, 1922.

Application filed June 6, 1921. Serial No. 475,543.

To all whom it may concern:

Be it known that I, MICHAEL H. SULLIVAN, a citizen of the United States, residing at Poughkeepsie, in the county of Dutchess 5 and State of New York, have invented certain new and useful Improvements in Pistons and Piston Rings; and I do declare the following to be a full, clear, and exact description of the invention, such as will enable others skilled in the art to which it 10 appertains to make and use the same.

This application relates to improvements in pistons and piston rings and constitutes a continuation in part of my pending U. S. 15 application Serial No. 462,109 filed on or about April 18, 1921.

One object of the invention is to provide an improved piston ring and a novel piston construction associated therewith, so that 20 the expansion of the ring into constantly tight contact with the cylinder wall, is not dependent upon the inherent resiliency of the ring but is effected by means of a suitable spring carried by the piston, the ring 25 being formed of two semi-circular sections forced outwardly by the same spring, so as to equalize the pressure on both of said sections.

A further object is to provide sealing 30 blocks for the spaces between the ends of the ring sections and to provide co-acting means on said blocks and ring sections to force the former always into tight contact with the cylinder wall. This co-acting means prefer- 35 ably consists of ribs carried by the sealing blocks and grooves in the ring sections slid- ably receiving said ribs and a further aim is to pivotally mount the ribs to facilitate as- 40 sembly of the rings in the piston groove, as well as to allow free movement of the ring sections in partially adapting themselves to the cylinder walls.

With the foregoing and minor objects in 45 view, the invention resides in the novel construction and association of parts herein- after described and claimed, the descriptive matter being supplemented by the accom- 50 panying drawings.

Figure 1 is a transverse sectional view

through the improved piston and the por- 50 tion of its retaining cylinder, showing the piston ring and its expanding means in elevation.

Figure 2 is a longitudinal sectional view 55 of the piston, cylinder and associated parts, as indicated by line 2—2 of Fig. 1.

Figure 3 is a perspective view showing the two sections of the piston ring in juxtaposition.

Figure 4 is a detail sectional view as indi- 60 cated by line 4—4 of Fig. 1.

Figure 5 is a perspective view of one of the sealing blocks.

Figure 6 is a perspective view of one of the heads which are thrust outwardly by 65 spring tension to force the ring sections into tight contact with the cylinder.

Figure 7 is a duplicate of Fig. 1 with the exception that it illustrates a modified form 70 of construction.

In Figs. 1 to 6 of the drawings above briefly described, I have shown a piston 1 contained in a cylinder 2, said piston having spaced ring grooves 3. The piston rings are each formed of two semi-circular sections 4 75 across whose centers, semi-cylindrical exten- 80 sions 5 of cylindrical heads 6 extend, said heads having rounded outer ends 7 for contact with the inner edges of the ring sections to permit any necessary tilting of the latter 85 with respect to the heads. Studs 8 extend in- 90 wardly from the heads 6 and said heads and studs are received in diametrically positioned tubes 9 which extend across the in- 95 terior of the piston 1 and are preferably lo- cated at right angles to each other as shown, thereby causing the ring sections 4 to break joints with the next adjacent ring. The tubes 9 are preferably cast integrally with the piston 1 but this is not altogether es-

sential, said tubes being provided for the purpose of housing coiled springs 10 which act oppositely against the ring sections 4 to force them into tight contact with the cyl- 95 inder wall, the ends of the springs being po- sitioned in contact with the heads 6 and sur- rounding the studs 8 as shown fully in Figs. 1 and 2.

For sealing the spaces between the ends of the ring sections 4, I provide semi-cylindrical blocks 11 whose flat sides overlap and are positioned in tight contact with one flat side 5 of the ring sections, said blocks 11 being received in appropriate recesses 12 which are formed in the piston 1 and open into the ring grooves 3. The flat side of each block 11 is provided with a curved rib 13 pivoted 10 thereto at 13^a, and the ring sections 4 are provided with grooves 14 concentric with said sections and slidably receiving the ribs of said blocks. The grooves 14 preferably extend throughout the length of the ring 15 sections 4 to facilitate manufacture and provide a lighter ring, and in order to prevent circumferential creeping of said ring sections upon the ribs 13, I provide a pair of stop pins 14^a in one of the grooves.

As will be seen most clearly by reference to Fig. 1, the co-acting ribs and grooves 13 and 14 not only prevent any inward movement of the sealing blocks 11 from the cylinder walls, but these parts crowd said 25 sealing blocks outwardly as the spring 10 separates the ring sections 4 and holds them in tight contact with the cylinder. An absolutely non-leaking piston ring is thus provided and attention is directed to the fact 30 that this ring does not rely on its inherent resiliency to hold it in contact with the cylinder, all expansion of the ring being effected by a spring of suitable tension, said spring acting oppositely on the two ring sections 35 so as to hold them in contact with the cylinder wall under precisely the same pressure. As the ring sections 4 wear slightly and are moved outwardly by the spring 10, the co-acting ribs and grooves 13 and 14 crowd the sealing blocks 11 outwardly and 40 at all times hold them in tight contact with the wall of the cylinder to prevent leakage.

I wish to direct particular attention to the fact that the ribs 13 are pivoted to the sealing blocks 11. This is not only of advantage in assembling the ring sections in the ring groove, but it permits any necessary movement of said ring sections in properly adapting themselves to the cylinder. Since the 45 sections 4 are not secured to the heads 6 or their extensions 5 and may rock slightly on the rounded ends 7 of said heads, their movement is not interfered with in any manner.

The pistons and rings as shown may all 55 be standard, that is, different sized pistons can have grooves of the same width and depth, and the recesses 12 and tubes 9 may be of uniform size, so that rings of standard dimensions, with the exception of their diameter, may be manufactured for use on pistons of numerous sizes, without the necessity of changing any dimensions except the diameter.

In the form of construction shown in Fig. 60 7 two ring sections 4^a are pivoted together

at one end as shown as 4^b and are sealed at their other ends by one of the blocks 11 above described. With the exception of pivoting the ends of the ring sections together instead of having the both ends free of attachment to each other, the construction shown in Fig. 7 is identical with that above described and hence further explanation is unnecessary.

Since excellent results are being obtained 75 from the details disclosed, these details may well be followed. It is to be understood, however, that within the scope of the invention as claimed, numerous minor changes may be made.

I claim:

1. The combination with a piston having a ring groove; of a piston ring in said groove diametrically split into two semi-circular relatively movable sections, and a single coiled 85 spring extending diametrically across said piston and acting on the centers of said ring sections to force them into uniform contact with the cylinder wall.

2. The combination with a hollow piston 90 having a groove; of a tubular guide extending across the interior of said piston and communicating at its ends with said groove at diametrically opposite points, a piston ring in said groove divided diametrically into two 95 relatively movable semi-circular sections, cylindrical heads bearing against the inner edges of said sections and having semi-cylindrical extensions resting against one flat side of said ring sections at their central portions, 100 said heads being slidably received in said tubular guide, and a coiled spring in said guide acting oppositely against said heads, whereby to force the two ring sections outwardly into uniform contact with the cylinder walls. 105

3. The combination with a piston having a piston groove; of a piston ring in said groove divided into relatively movable sections, said piston having a recess at the meeting ends 110 of said sections, a sealing block in said recess in tight contact with one flat side of said ring section, spring means for forcing said ring sections against the cylinder wall and co-acting means on said ring sections and sealing block for utilizing the action of said 115 spring means and the movement of said sections to force said block outwardly against the cylinder wall.

4. The combination with a piston having a ring groove; of a piston ring in said groove 120 divided into relatively movable sections, said piston having a recess at the meeting ends of said sections opening into one side of said groove, a flat-sided radially movable sealing block located in said recess and contacting 125 with one flat side of said ring sections, and an arcuate rib on said sealing block, said ring sections having grooves slidably receiving said rib, and spring means for forcing the ring sections outwardly into tight con- 130

tact with the cylinder wall and thereby causing the rib and grooves to force said sealing block outwardly.

5. A structure as specified in claim 4, said 5 rib being pivoted to said sealing block.

6. A piston ring divided into a pair of 10 relatively movable sections, the adjacent ends of said sections having grooves in one flat side, a sealing block having a flat side contacting with said side of said ring sections, and an arcuate rib pivoted to said sealing block and having its ends slidably received 15 in said groove.

7. A semi-cylindrical sealing block of the 15 type set forth, having a rib pivoted to and extending transversely across its flat side.

8. A spring-actuated ring expanding de-

vice comprising a cylindrical head having a semi-cylindrical extension at one end and a projecting stud at its other end, the exposed 20 portion of said one end being rounded for contact with the inner edge of said piston ring section.

9. A hollow piston having a plurality of 25 ring grooves, and a plurality of tubes extending diametrically across said piston and communicating with said grooves, said tubes being adapted to contain ring-expanding springs and being disposed in intersecting planes. 30

In testimony whereof I have hereunto set my hand.

MICHAEL H. SULLIVAN.
